US0D1011325S

(12) **United States Design Patent** (10) **Patent No.:** **US D1,011,325 S**
(45) **Date of Patent:** **** Jan. 16, 2024**

(54) **ANTENNA**

(71) Applicant: **Comrod Communication AS**, Tau

(NO)

(72) Inventor: **Velid Omerovic**, Jørpeland (NO)

(73) Assignee: **Comrod Communication AS**, Tau

(NO)

(**) Term: **15 Years**

(21) Appl. No.: **29/778,669**

(22) Filed: **Apr. 14, 2021**

(51) **LOC (14) Cl.** **14-03**

(52) **U.S. Cl.**

USPC **D14/230**

(58) **Field of Classification Search**

USPC D14/230, 231–240, 400, 138, 299, 358;
D13/133, 154; D12/43, 42

CPC H01Q 1/1241; H01Q 1/246; H01Q 1/42;
H01Q 1/02; H01Q 121/28

See application file for complete search history.

(57) **CLAIM**

The ornamental design for an antenna, as shown and described.

DESCRIPTION

FIG. 1 is a perspective view of a first embodiment of an antenna according to my new and ornamental design;

FIG. 2 is a side view thereof;

FIG. 3 is an opposite side view thereof;

FIG. 4 is a rear view thereof;

FIG. 5 is a front view thereof;

FIG. 6 is a top view thereof;

FIG. 7 is a bottom view thereof;

FIG. 8 is a perspective view of a second embodiment of an antenna according to my new and ornamental design;

FIG. 9 is a side view thereof;

FIG. 10 is an opposite side view thereof;

FIG. 11 is a rear view thereof;

FIG. 12 is a front view thereof;

FIG. 13 is a top view thereof;

FIG. 14 is a bottom view thereof;

FIG. 15 is a perspective view of a third embodiment of an antenna according to my new and ornamental design;

FIG. 16 is a side view thereof;

FIG. 17 is an opposite side view thereof;

FIG. 18 is a rear view thereof;

FIG. 19 is a front view thereof;

FIG. 20 is a top view thereof; and,

FIG. 21 is a bottom view thereof.
